DESIGN FOR A WRENCH

Harry B. Curtis, Huntington, Conn., assignor to
The Bridgeport Hardware Manufacturing Cor-
poration, Bridgeport, Conn., a corporation of
Connecticut

Application September 21, 1935, Serial No. 58,655

Term of patent 7 years

To all whom it may concern:

Be it known that I, Harry B. Curtis, a citizen
of the United States, residing at Huntington,
county of Fairfield, State of Connecticut, have
invented a new, original, and ornamental Design
for a Wrench, of which the following is a specifica-
tion, reference being had to the accompanying
drawing, forming part thereof.

Fig. 1 is a plan view of a wrench, showing my
new design.

Fig. 2 is an edge view thereof.

I claim:

The ornamental design for a wrench, substan-
tially as shown.

HARRY B. CURTIS.
